Inventor.

W. C. McGill

United States Patent Office.

WILLIAM C. McGILL, OF CINCINNATI, OHIO.

Letters Patent No. 77,506, dated May 5, 1868.

IMPROVED BLACKING-BRUSH.

The Schedule referred to in these Letters Patent and making part of the same.

TO WHOM IT MAY CONCERN:

Be it known that I, WILLIAM C. McGILL, of Cincinnati, Hamilton county, Ohio, have invented a new and useful Blacking-Brush; and I hereby declare the following to be a full, clear, and exact description thereof, reference being had to the accompanying drawings, making part of this specification.

Figure 1 is a perspective view of a brush embodying my invention.

Figure 2 is a longitudinal section of the front end of the same; and

Figure 3 is a perspective view of the standard.

A and B represent respectively the stock or handle and the brush proper, and may be of any approved form.

In the place and stead of the ordinary spreading-brush, I provide a cylindrical brush, C, whose gudgeons, c, are made to occupy apertures, d or d', in steel-spring standards, D D', made fast to the back of the stock. The standards D D' are provided with lips, d'', which embrace but permit the rotation of a common blacking-box, E.

The action of my improvement is as follows: A box of blacking, E, without its lid, is pressed in between the standards D D', and the cylindrical brush, C, inserted, with its gudgeons, c, in the upper holes of the standards.

The brush C is then rubbed briskly over the boot or shoe to be blacked, and applied to all parts of the latter until the same is coated with blacking, after which the polishing is effected by means of the brush proper, B, as usual.

F is a cover, adapted to be closed snugly over the spreading-brush and blacking-box when not in use. The box E, being partially rotated between the times of using, enables the cylindrical brush to reach every part, and thus use up the entire contents.

While preferring steel for the material of the standards, I reserve the right to employ brass or other suitable material. Again, one or both of the standards may be of cast iron or other rigid material, and may be adjusted in or out by means of a slot and screw.

I claim herein as new, and of my invention—

1. In combination with the spreading-brush, the cover, made and operating substantially as and for the purpose herein described.

2. The spring-standards D D', serving the double purpose of journaling the said brush, and of holding while permitting the adjustment of the blacking-box, operating substantially as herein shown and described, and for the purpose set forth.

In testimony of which invention, I hereunto set my hand.

WM. C. McGILL.
